UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRIC SWITCH.

Application filed July 3, 1922. Serial No. 572,527.

This invention relates to an electric switch particularly adapted, although not limited, to the control of small induction motors.

An induction motor, when starting, requires momentarily a considerably greater current than when running at full load, and the current carried by the contact members of the control switch during the starting period is greater than the current carried 10 during the running period of the motor, and also greater than the current due to the usual motor overload. The contact members, therefore, are required to complete the motor circuit under more adverse conditions than 15 to interrupt the circuit, even under usual overload conditions.

An object of this invention is to provide a switch whereby the circuit is completed in an effective manner to reduce arcing at the 20 contact members due to the heavy starting current, and specifically, to provide a switch arranged to complete the circuit rapidly; and the switch may open the circuit at a more moderate speed.

25 A further object is to provide simple and effective manually-controlled switch operating mechanism including a spring arranged to close the switch rapidly and hold it yieldingly in both open and closed positions.

30 A further object is generally to improve the construction and operation of electric switches.

This invention is described but not claimed in a co-pending application of George W. 35 O'Keefe, Serial No. 572,536, filed July 3, 1922, and assigned to Sears B. Condit.

Fig. 1 is a sectional elevation of the switch embodying the invention.

Fig. 2 is a section along line 1—1 of Fig. 2.

40 As here shown, the switch embodying the invention may include the casing having the upper casing portion 10 and the lower casing portion 11 which is adapted to contain oil in which the switch members are immersed. A supporting plate 12, which may be made of suitable insulating material, as porcelain, is or may be received within the upper casing portion 10 and is adapted to support the switch components.

45 The stationary switch members may comprise the relatively flexible strip-members 14 and 15 which are secured to and depend from the lower face of the supporting plate,

and said members may be reflexed outwardly and terminate in the detachable contact 55 members 16 and 17.

The movable switch member may include the arm 18 which may be pivotally supported in a bracket 19, and said bracket may be secured to and depend from the lower 60 face of said supporting plate. An insulating bar 20 may be secured to the free end of said arm 18 and a contact or bridging member 21 may be secured to said bar 20. Said contact member 21 is adapted to be moved 65 upwardly to engage said stationary contact members 16 and 17.

The switch operating mechanism embodying my invention may include a, preferably 70 tension, spring 25 which may be connected to an ear 26 of the arm 18 and an ear 26* of a plate 27 secured to the lower face of the circulating plate, and, in accordance with my invention, said spring is arranged to bias the switch toward closed position and 75 constantly urge the arm 18 upward to move the contact member 21 to engage the stationary contact members 16 and 17. Means are provided to permit said spring to act, 80 whereby to close the switch, or to restrain it from acting, whereby to hold the switch open. Said means may include the toggle member including the links 30 which are 85 pivotally connected with the crank arm 31. Said links 30 are pivotally connected with the switch arm 18 and said crank arm 31 is fixed to an operating shaft 32, and said shaft may be rotatably supported in ears 33 struck up from said plate.

Said toggle is so arranged that, in the 90 straightened position it is slightly overshot, as indicated in Fig. 1, and holds the switch open against the urge of said spring 21 but, when the operating shaft 32 is rotated in a 95 clock-wise direction to move the toggle over the dead center, said spring 25 acts to close the switch rapidly. The closed position of the switch is indicated in the dotted lines, Fig. 1.

100 Means are provided to restrict the movement of the switch in open and closed positions and said means may comprise the ears 35 and 36 which may be struck up from said plate 27 and disposed on opposite sides of the crank arm 31. Said crank arm 31 may 105 engage the ear 36 to fix the switch-open posi-

tion of the movable switch member, and said crank may engage the ear 35 to fix the switch closed position of the movable switch member.

5 Said spring and toggle are so arranged that the toggle is held yieldingly by the spring in positions corresponding both to closed and open positions of the switch.

10 The operating shaft 32 may be rotated by suitable externally disposed means as the key 40 which may extend through an aperture in the upper casing portion 10 and be received on the end of the shaft and loosely connected therewith as by the screw 41 in the end of the shaft which is received loosely in the angularly elongated slot 42 in the key 40. The arrangement is such that a rotary movement of said key serves to rotate the shaft to move the toggle over the dead center 15 and the spring therefore snaps the switch into closed position independently of further control from the key. The key, however, must rotate the shaft through its full extent of rotary movement in the opposite 20 direction to open the switch.

25 It is obvious that the structure may be modified without departing from the spirit of the invention.

I claim:

30 1. In an electric switch including an enclosing casing, movable and stationary switch members and operating mechanism received therein, said movable switch member comprising a pivoted arm, said operating mechanism including means to urge the switch members together, a rotatably supported operating shaft extended externally 35 beyond the casing, links comprising a toggle connecting said operating shaft and pivoted arm arranged to govern the action of said urging means, and an operating member

connected loosely with said shaft externally of said casing.

2. In an electric switch, movable and stationary switch members, said movable switch member comprising a pivoted arm, and switch operating mechanism including a rotatably supported operating shaft, and links comprising a toggle connecting said operating shaft and pivoted arm, a spring associated with said pivoted arm arranged to urge said arm constantly toward switch closed position, said toggle arranged to govern the action of said spring, and an operating member having a loose connection with 45 said shaft, whereby to permit said switch to be closed by said spring independently of a corresponding movement of said operating member. 50

3. In an electric switch including an enclosing casing, movable and stationary switch members and operating mechanism received therein, said movable switch member comprising a pivoted arm, said operating mechanism including a rotatably supported 55 operating shaft extended externally beyond the casing and links comprising a toggle connecting said operating shaft and pivoted arm, a spring associated with said pivoted arm arranged to urge said arm constantly 60 toward switch closed position, said toggle arranged to govern the action of said spring and an operating member disposed externally 65 of said casing having a loose connection with said operating shaft whereby to permit said spring to close the switch independently 70 of a corresponding movement of said operating member. 75

In testimony whereof, I have signed my name to this specification.

GEORGE A. BURNHAM.
